UNITED STATES PATENT OFFICE.

WILLIAM S. HAMM, OF CHICAGO, ILLINOIS.

LANTERN.

SPECIFICATION forming part of Letters Patent No. 594,790, dated November 30, 1897.

Application filed March 2, 1897. Serial No. 625,755. (No model.)

To all whom it may concern:

Be it known that I, WILLIAM S. HAMM, of Chicago, in the county of Cook and State of Illinois, have invented certain new and useful Improvements in Lanterns, of which the following is a specification, reference being had to the accompanying drawings and to the numerals of reference marked thereon.

My invention relates to an improvement in hand-lanterns such as are more commonly used by conductors, brakemen, and railroad-men generally.

The objects of my invention are to improve the construction of the upper portion of the device and to increase the illuminating qualities of the lantern, whereby a bright steady flame may be maintained and the liability of its being blown out or extinguished by a sudden or quick lifting movement or by jar or shock is reduced to the minimum.

The first part of my invention has reference to a cap having a wind-cone for deflecting the air that enters the outlet-openings in the cap when the lantern is exposed to strong winds and if not properly deflected will extinguish the flame or reduce its steadiness and illuminating effect. This feature of my invention obviates this danger, the air being caused to pass over the top of the globe or chimney without injuriously affecting the flame. All danger of extinguishment as the lantern is suddenly lifted is also prevented, the quick inrush of air, which under other constructions would pass into the globe or chimney, being broken and deflected.

The second part of my invention relates to a simple and efficient device whereby the wind-cone, which by spring action presses upon and adjusts itself to the upper edge of the globe as the hinged cap is closed down, may be readily detached from the cap for purposes of cleaning or otherwise and as easily replaced.

In the accompanying drawings, Figure 1 is an elevation of my improved lantern. Fig. 2 is a section thereof on the line 2-2. Fig. 3 is an interior view of the top. Figs. 4 to 10, inclusive, illustrate details and modifications.

Similar numerals of reference indicate similar parts in the respective figures.

In all forms of my invention as herein shown the base 1, lamp 2, globe or chimney 3, wire

guard-frame 4, and top or cap 5, except as hereinafter specified, may be of any construction at present found in approved types of 55 the lantern.

Referring to Figs. 1, 2, and 3, within the cap 5 is a wind cone, breaker, or deflector 6, adapted to slide vertically, its lower edge embracing the globe or chimney 3 and holding the 60 same firmly in place by means of a spiral spring 11 within the cap and bearing on the wind-cone 6. The wind-cone consists of a shell of thin metal, its lower part being cylindrical, while its upper portion is of frusto- 65 conical shape, through the open top of which the products of combustion pass into the cap 5 and thence out of the lantern through the perforations 10, formed in the cap, as shown.

Riveted within the cone, near the top, and on opposite sides thereof, are two spring-arms 9, 9, extending downwardly to a point near the bottom. Pins 9^a, one secured to the lower end of each spring-arm, pass through perforations 13, 14, formed, respectively, in 70 the wind-cone 6 and the cap 5. Finger-pieces 12, attached to the spring-arms, afford means for withdrawing the pins from the perforations 14 in said cap when it is desired to remove the wind-cone from the cap to clean it 75 or for any other purpose. If preferred, the finger-piece 12 may be formed of a continuous strip of metal having a loop in the center, as indicated in dotted lines in Fig. 2 and in full lines in Fig. 10. 85

The openings 14 in the cap 5 are elongated, and in this form of my invention stand in an inclined position, and the wind-cone, as the hinged cap is forced down and clasped to the upper edge of the wire guard, will be given 90 not only an upward movement as the spiral spring 11 is compressed, but also a slight rotary movement, the pins 9^a riding up the inclined openings or slots 14.

In Fig. 4 the slots 14 in the cap for the pins 9^a are arranged vertically and the slight rotary movement just referred to is not occasioned.

In Fig. 5 but one spring-arm 9 is shown, and consequently only one pin 9^a; but a stud 100 or pin 9^b is attached to the opposite side of the wind-cone, extending through its slot 14 in the cap. To remove the cone, the pin of the spring-arm must first be withdrawn from

its cap-slot 14, after which the cone will be ejected by the force of the spring, the pin 9^b being removed from its slot 14 by this action. In Fig. 6 the same construction is found, except that the pin 9^b is secured to the cap instead of the cone, the latter being slotted to receive the pin.

In the modification seen in Figs. 7 and 8 attached to the outside of the cap 5 in the position shown is a flat spring 9^c, its free end being turned out to form a finger-catch and which has the pin 9^a secured thereto, extending through a hole in the cap and the slot in the cone. A guard or stop 10 may be fastened to the cap to limit the outward movement of the spring. A stud 9^b is oppositely secured to the inside of the cap and is adapted to enter the corresponding slot of the wind-cone. When the cap 5 has been turned up, the spring 11 would force the wind-cone out of the cap but for the pin 9^a and stud 9^b, which engage with the slots of the wind-cone. When the removal of the wind-cone is desired, the operator retracts the spring 9^c, thus withdrawing the pin 9^a from its engagement with its cone-slot. This releases the wind-cone and allows the spring to force it out of the cap. The wind-cone is readjusted by placing it in the cap and pushing it up until the proper slot of the cone engages with the stud 9^b. The spring 9^c is then bent outwardly, withdrawing the pin 9^a. Now by pushing the wind-cone into place and releasing the free end of the spring the pin 9^a will enter its slot in the wind-cone and the latter will be secured in position.

I sometimes dispense with a spring to force the wind-cone down upon the chimney, in which case, as illustrated in Figs. 9 and 10, the upper edge of each of the inclined slots 14^a is serrated to engage and hold one of the pins 9^a when the wind-cone is turned to secure the globe or chimney in place. It will be understood that by turning the cone it may be brought to its proper vertical position with respect to the globe or chimney and locked in such position by the engagement of the pins 9^a with the serrations.

While my invention is here shown in con-

nection with a "railroad-lantern," so called, it is to be understood that I do not wish to limit it to such, but reserve the right to use it with any style of lamp or lantern to which it is applicable.

Having thus described my invention, I claim—

1. In a lantern, the combination of a cap, a removable wind-cone adapted to move vertically therein, and a spring-actuated pin arranged to enter a suitably-disposed opening in the cap and the wind-cone, substantially as described.

2. In a lantern, the combination of a cap having slots, as 14, a wind-cone adapted to move vertically within the cap and be removed therefrom, spring-actuated pins secured to the wind-cone and arranged to pass through openings in the cap, and through the slots 14, substantially as described.

3. In a lantern, the combination of a perforated cap having slots 14, a wind-cone adapted to move vertically within the cap, and be removed therefrom, its upper end being above the perforations in the cap, springs secured to the wind-cone and provided with pins adapted to pass through openings in the cap, and through the slots 14, and finger-pieces for actuating the spring, substantially as described.

4. In a lantern, the combination of a perforated cap, a removable wind-cone adapted to move vertically within the cap, springs secured at one end to the wind-cone, and provided with pins and finger-pieces, the said pins arranged to pass through the openings in the wind-cone and the cap for retaining the wind-cone in place, means for forcing the wind-cone from the cap when the pins are withdrawn from the openings, and a chimney upon which the wind-cone presses, substantially as described.

In testimony whereof I have hereunto set my hand and affixed my seal, at the said city of Chicago, this 15th day of February, 1897.

WILLIAM S. HAMM. [L. S.]

In presence of—

HENRY O. MILLER,
LOUIS A. GRAY.
